C. E. HAWKE

HEAT TRANSFER APPARATUS

Filed Feb. 17, 1923

UNITED STATES PATENT OFFICE.

CLARENCE E. HAWKE, OF METUCHEN, NEW JERSEY, ASSIGNOR TO THE CARBORUNDUM COMPANY, OF NIAGARA FALLS, NEW YORK, A CORPORATION OF PENNSYLVANIA.

HEAT-TRANSFER APPARATUS.

Application filed February 17, 1923. Serial No. 619,626.

Be it known that I, CLARENCE E. HAWKE, a citizen of the United States, residing at Metuchen, county of Middlesex, and State of New Jersey, have invented a new and useful 5 Improvement in Heat-Transfer Apparatus, of which the following is a full, clear, and exact description.

This invention relates to heat transfer transfer apparatus, and is particularly 10 adapted for use in constructions where fuel is burned inside a combustion space or passage, the walls of which transfer the heat of combustion to a surrounding space.

Heretofore it has been very hard, if not 15 impossible, to maintain such constructions in continuous working order, because the flames from the burner generally tend to impinge on one side of the combustion passage. This results in unequal expansion and con- 20 traction, eventuating in a cracking of the passage. This is particularly true where refractory tubes are employed.

My invention provides an inner sleeve or 25 lining for protecting the faces of the heat transfer walls, thereby preventing a direct impingement of the flame and highly heated gases and eliminating the difficulties occasioned thereby. The protecting sleeve is 30 preferably constructed of a material of high thermal conductivity, such as silicon carbide, and should also be free to expand and contract independent of the tube or passage proper.

My invention further provides ready 35 means for the removal and replacement of the protecting sleeve when occasion demands.

In the accompanying drawings, illustrating 40 the present preferred embodiment of my invention:

Figure 1 is a sectional view illustrating my invention as applied to a furnace,

Figure 2 is a section on the line II-II of Figure 1, and

Figure 3 is a perspective view of a detail 45 of my invention.

In the illustrated embodiment of my invention a combustion chamber or passage 2 projects through the wall 3 of a furnace into the working chamber or interior 4 which is to be heated by conduction of heat through the walls of the passage 2. It will be understood that a plurality of such passages may be employed according to the require-

ments of any particular installation. The 55 passage 2 includes a section 5 which is of refractory material, such as silicon carbide, and is preferably circular in cross section. Further units or tubes 6 may be supplied to extend the passage 2 to any desired length. 60 The sections 5 and 6 are joined by an insert 7 which is cemented into the section 5. The bell mouth 8 of the section 6 is then placed over the projecting end of the insert 7, and the sections 5 and 6 are cemented together 65 to secure a gas tight joint. The other end of the section 5 is inserted a short distance into the furnace wall 3 and is cemented 70 therein, as shown at 9. Another section 10, whose length is substantially the thickness 75 of the wall, is introduced into the bell mouth 11 of the section 5 to continue the passage to the outside of the furnace. An annular rib 12 is provided on the outside of the section 10, and this annular rib has beveled 80 edges adapted to co-operate with the outer end of the bell mouth 11 to form a tight joint. The joint is, however, cemented as shown at 13 to obviate any possibility of leakage. A burner 14 of any type, depend- 85 ing on the fuel employed, is placed outside the furnace and directed along the axis of the passage 2.

I have found, however, that in practice the flame does not coincide with the axis, 85 and in any event spreads considerably in the passage 2, with the result that there is generally a more or less concentrated impinge- 90 ment on one portion of the passage, tending toward cracking and rapid destruction of the apparatus. To overcome this, I provide a lining 15 for the section 5. This lining is tapered at the end adjacent the burner 14 to provide a smooth passage for the gases with no abrupt changes in cross section, and the 95 lining 15 at its further end is inset in the insert 7 for the same purpose.

The lining 15 is constructed of a material of high thermal conductivity, such as silicon carbide. Moreover, it is free to expand or 100 contract independent of the passage section 5, and is maintained co-axial therewith by placing it on a bed of loose granular silicon carbide or other refractory 16. This construction eliminates the breakage generally 105 encountered in such apparatus, not only because it prevents impingement of the flame upon the passage wall proper, but also

because it reduces the temperature of the first section 5, and tends to equalize the temperature of all the sections of the passage 2.

- 5 Since there is a great temperature difference between the inside and outside of the furnace wall, there has heretofore been a considerable tendency toward cracking of a passage when extended through the wall.
- 10 The provision of the separate section 10, which continues the passage through the wall while the working section 5 is extended only a short distance into the wall, localizes such a cracking tendency in the section 15 10. This section may be readily removed by breaking away the cement 13 as occasion requires. Moreover, by breaking away the cement 9, the passage 2 may be removed entire, as will be apparent from the drawings.

20 While I have shown one embodiment of my invention, it will be understood that it is not limited thereto, but may be embodied in other constructions within the scope of the following claims.

25 I claim:

1. Heat transfer apparatus, comprising a heating chamber, and a combustion chamber extending within said heating chamber and having refractory heat transfer walls, said combustion chamber having a separable inner lining for at least a portion of its length, substantially as described.
- 30 2. Heat transfer apparatus, comprising a heating chamber, and a combustion chamber extending within said heating chamber and having refractory heat transfer walls, said combustion chamber having a separable inner lining for at least a portion of its length, substantially as described.
- 35 3. Heat transfer apparatus, comprising a heating chamber, and a combustion chamber extending within said heating chamber and having refractory heat transfer walls, said combustion chamber having a separable lining of refractory material for at least a portion of its length, substantially as described.
- 40 4. Heat transfer apparatus, comprising a heating chamber, and a combustion chamber extending within said heating chamber and having refractory heat transfer walls, said combustion chamber having a separable inner lining for at least a portion of its length, substantially as described.
- 45 5. Heat transfer apparatus, comprising a heating chamber, and a combustion chamber extending within said heating chamber and having refractory heat transfer walls, said combustion chamber having a separable inner lining for at least a portion of its length, substantially as described.
- 50 6. Heat transfer apparatus, comprising a heating chamber, and a combustion chamber extending within said heating chamber and having refractory heat transfer walls, said combustion chamber having a separable inner lining for at least a portion of its length, said lining being mounted within said combustion chamber in such manner as to permit it to expand and contract independently of the walls of said combustion
- 55 7. Heat transfer apparatus, comprising a heating chamber, and a combustion chamber extending within said heating chamber and having refractory heat transfer walls, said combustion chamber having a separable inner lining for at least a portion of its length, said lining being loosely supported within said combustion chamber on a bed of granular material, substantially as described.
- 60 8. Heat transfer apparatus, comprising a heating chamber, and a combustion chamber extending within said heating chamber and having refractory heat transfer walls, said combustion chamber having a separable inner lining of refractory material for at least a portion of its length, said lining being loosely supported within said combustion chamber on a bed of granular material of high thermal conductivity, substantially as described.
- 65 9. Heat transfer apparatus, comprising a heating chamber, and a combustion chamber extending within said heating chamber and having refractory heat transfer walls, said combustion chamber having a bodily removable loosely mounted lining of refractory material for a portion of its length, substantially as described.
- 70 10. Heat transfer apparatus, comprising a heating chamber, and a combustion chamber extending within said heating chamber and having refractory heat transfer walls, said combustion chamber having a bodily removable tubular inner lining of refractory material for at least a portion of its length, substantially as described.
- 75 11. Heat transfer apparatus, comprising a heating chamber, and a combustion chamber extending within said heating chamber and having refractory heat transfer walls, said combustion chamber having an opening in the end thereof within said wall opening for the introduction of fuel and having a removable inner lining for a portion of its length adjacent said fuel opening, substantially as described.
- 80 12. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 85 13. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 90 14. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 95 15. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 100 16. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 105 17. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 110 18. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 115 19. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 120 20. Heat transfer apparatus, comprising a heating chamber having an opening through a wall thereof, a combustion chamber within said opening and projecting into said heating chamber and having refractory heat transfer walls, said combustion chamber having an opening in the end thereof within said wall opening for the introduction of fuel and having a removable inner lining for a portion of its length adjacent said fuel opening, substantially as described.
- 125 21. Heat transfer apparatus, comprising a heating chamber having an opening through a wall thereof, a combustion chamber within said opening and projecting into said heating chamber and having refractory heat transfer walls, said combustion chamber comprising a section projecting into said heating chamber and having its outer end portion sealed into said opening and a second section within said opening, said sec-

ond section having its inner end portion seated within the outer end portion of the first section, substantially as described.

12. Heat transfer apparatus, comprising a heating chamber having an opening through a wall thereof, and a tubular combustion chamber extending within said opening and projecting into said chamber and having refractory heat transfer walls, said combustion chamber comprising a section projecting into said heating chamber and having its outer end portion sealed into said opening

and a second section within said opening, said second section having its inner end portion seated within the outer end portion of the first section and a removable tubular lining of refractory material for said first section, said lining covering the joint between said sections, substantially as described.

20 In testimony whereof I have hereunto set my hand.

CLARENCE E. HAWKE.
